UNITED STATES PATENT OFFICE.

CARL T. TOBIASON AND OLOF SWANSON, OF Sycamore, Illinois; SAID TOBIASON
ASSIGNOR TO SAID SWANSON.

SUPPORTING-CLAMP.

1,301,885.

Specification of Letters Patent. Patented Apr. 29, 1919.

Application filed June 13, 1917. Serial No. 174,559.

To all whom it may concern:

Be it known that we, CARL T. TOBIASON and OLOF SWANSON, of Sycamore, in the county of Dekalb and State of Illinois, have 5 invented certain new and useful Improvements in Supporting-Clamps, of which the following is a specification.

This invention relates to improvements in supporting clamps. One object of the invention is to provide novel means whereby advertising cards, signs, announcements and the like may be readily suspended from surfaces not ordinarily accessible for this purpose, such as store windows, glass door 15 panels and the like, without in the least damaging or defacing the supporting surface. With the foregoing and other objects in view the invention consists in the combination and arrangement of parts to be hereinafter fully described, pointed out in the appended claims and illustrated in the accompanying drawing which forms a part of 20 this specification and in which—

Figure 1 is a front view of the supporting clamp illustrating its application.

Fig. 2 is a perspective view of the clamping element illustrating its application.

Fig. 3 is a fragmentary view of a slightly modified form of clamping device showing 30 its application.

Fig. 4 is an enlarged fragmentary view of Fig. 3 taken at the point denoted by the arrow 4.

Like reference characters denote corresponding parts throughout.

Our supporting clamp includes a rubber suction cup 1 which, upon being pressed against a window pane or similar smooth surface 2, will adhere thereto in a well 40 known manner. The cup 1 is provided with a pin 3 which carries an inverted substantially U-shaped bracket 4, said pin extending through apertures 5 formed in said bracket. The sides of the bracket from its 45 free ends are formed with regular waves or undulations throughout the greater part of their length and teeth 6 are punched from said sides thus forming, in said sides, the apertures 7. The teeth 6 are spaced apart

and are formed in the outwardly bulged 50 portions of the regularly curved sides and between said teeth the claws 8 are secured by hinges 9 to the bracket 4. In the form shown in Figs. 1 and 2 the free ends of the claws have a bearing against the card or 55 device 10 and the teeth 6 also engage the device 10. In Figs. 3 and 4 the claws 8 are formed with apertures 11 through which the free ends of the teeth 6 may project for engagement with the card 10, 60 the teeth 6, when the sides of the bracket are pressed together, having a bearing upon the base of the apertured portions 11 of said claws. A ring 12 encompasses the bracket 4 and when moved toward the free ends of 65 the same will serve to force said ends toward each other thus driving the teeth and claws into positive engagement with each other and with the card 10 when it is desired that a very firm purchase upon the 70 same be had. It will be observed that the teeth 6 will serve effectually, when the binding ring 12 is applied to the sides of the bracket 4, to space the free ends of the claws 8 away from the bracket-sides and to 75 retain said claw-ends in engagement with the element 10.

What is claimed is:—

1. In a supporting clamp, a U-shaped bracket, teeth formed in the sides of said 80 bracket, movable claws carried by the sides of said bracket, and an annular binding element carried by said bracket.

2. In a supporting clamp, a U-shaped bracket, apertured claws hinged to said 85 bracket, teeth formed in the sides of said bracket and adapted to project through the apertures in said claws, and a binding ring adjustably carried by said bracket.

3. In a supporting clamp, a U-shaped 90 bracket, a binding ring adjustably carried by said bracket, apertured claws hinged to said bracket, and teeth formed in the sides of said bracket and projected through the apertures in said claws and, under pressure 95 of said binding ring, having a bearing upon the apertured portions of said claws.

4. In a supporting clamp, a U-shaped

bracket, a binding ring adjustably carried by said bracket, apertured claws hinged to said bracket and spaced away from each other, and inwardly bent teeth formed in 5 the sides of said bracket and projected through the apertures in said claws and, under pressure of said binding ring, having a bearing upon the apertured portions of said claws.

In testimony that we claim the foregoing 10 as our own we have hereto affixed our signatures in the presence of two subscribing witnesses.

CARL T. TOBIASON.
OLOF SWANSON.
